UNITED STATES PATENT OFFICE.

JAMES P. FISHER, OF BARTLESVILLE, OKLAHOMA, ASSIGNOR TO DOHERTY RESEARCH COMPANY, OF NEW YORK, N. Y., A CORPORATION OF DELAWARE.

APPARATUS FOR DRILLING OIL WELLS.

Application filed June 30, 1922. Serial No. 572,056.

To all whom it may concern:

Be it known that I, JAMES P. FISHER, a citizen of the United States of America, residing at Bartlesville, in the county of Washington, State of Oklahoma, have invented certain new and useful Improvements in Apparatus for Drilling Oil Wells; and I do hereby declare the following to be a full, clear, and exact description of the invention, such as will enable others skilled in the art to which it appertains to make and use the same.

This invention relates to apparatus for drilling wells, and more particularly to an apparatus for drilling oil wells, whereby the time required for drilling may be greatly reduced, and whereby the time during which the drill is in continuous use may be greatly increased.

The present invention is based upon the discovery that by setting up a local circulation of water near the bottom of a well during the drilling operation, and by the use of a special form of drill, the mudding up of the drill-bit may be prevented, and the drilling operation carried on at a much faster rate.

One of the main difficulties encountered in drilling operations is due to the mudding up or formation of mud pads on the drill-bit, which necessitates the frequent halting of drilling operations for the cleaning of the drill-bit. Due to this mudding up of the drill-bit there is a resultant dash pot action during the reciprocation of the drill, which not only increases the power required for operating the drill, but also renders the cutting stroke ineffective, because of the decrease in the force of the blow given by the drill-bit. Furthermore, the cutting action of the drill is greatly hindered by the presence of mud around the cutting edges of the bit.

It has been attempted by various means to overcome the difficulties in drilling operations due to the above causes, but thus far only partial success has been attained. The wells which are now drilled for the production of oil commonly attain a depth of 4000 feet or more, whereas in the early development of the oil industry wells were drilled generally to a depth of only a few hundred feet at the most. One form of a drill which was developed for the drilling of shallow wells, but which proved to be in-

effective for drilling deep wells, employed a hollow stem and bit in the drilling operation, and water was pumped down through the stem to assist in bringing up mud and drill cuttings to the surface of the wells. 60 This drill was inefficient when applied to the drilling of deep wells for the following reasons:

(1) In pumping water from the surface of the well to the bottom thereof of the 65 drill cuttings, sand, etc. were not carried to the surface by the return current of water, and only the clay and lighter dirt particles were washed to the surface.

(2) A second defect of the drill, when applied to the drilling of deep wells was due to the fact that clean water would not hold sand and drill cuttings in suspension and consequently there resulted an accumulation 70 of sand and heavier particles in the water 75 which greatly increased the power necessary to operate the drill, and also rendered the usual bailing operation necessary because the water would not bring the drilled material to the surface.

(3) Another defect which was perhaps of an even more serious nature than those above mentioned was the fact that in circulating water from the top of the hole, in prospecting for oil or gas, it subjected the 80 formation or area drilled through to heavy hydrostatic pressure, and under this condition there would frequently be no flow of 85 gas or oil even though it was present, and the pay strata would be drilled through 90 without any indication of its presence.

It is apparent for these reasons that this form of drill could not be employed for the drilling of deep wells due to its inherent 95 defects, and that another form of drill must be devised if the standard form of drill commonly used in deep well drilling was to be improved upon. It is well known that the standard drill is objectionable on account of the fact that it requires frequent cleaning, 100 and the necessity of frequent cleaning of the drill tools and bailing of the hole results in an exceedingly high-non-productive time element in well drilling.

The primary object of the present invention is to provide an apparatus whereby wells may be drilled in less time than with the drills heretofore employed, and whereby the non-productive time element may be substantially decreased.

Another object of the invention is to provide an apparatus whereby the cutting edge of the drill bit may be maintained substantially free from mud pads during the drilling process, and thereby decrease the power consumption required in drilling operations.

A further object of the invention is to provide an apparatus whereby drill cuttings may be more easily removed than in the usual method of drilling.

With these and other objects in view the invention consists in the features which will be pointed out in connection with the accompanying drawings, in which;

Fig. 1 shows a view in elevation partly in section of the improved drill tools at the bottom of a well;

Fig. 2 shows an enlarged view of the drill-bit looking in the direction of arrows 2-2 of Fig. 1;

Fig. 3 is a cross sectional view of the drill-bit taken on the line 3-3 of Fig. 1;

Fig. 4 is a cross sectional view of the drill-bit taken on the line 4-4 of Fig. 1.

In the drawings the drilling apparatus embodying the preferred form of the invention, is illustrated in connection with a diagrammatically represented well, indicated by the numeral 2. The drilling apparatus comprises a drill-bit having cutting edges 6 and 8, as shown in Figs. 1 and 2, and a shank or upper part of the drill-bit 10 which has a threaded connection with a hollow stem 14, which may be made up of a number of sections. Through the inner portion of the shank of the drill-bit is formed a passage 16, which communicates with flutes 18 and 20 through passages 22 and 24, as shown in the drawings. The flutes of the drill-bit are provided with cover plates 26 and 28, which are attached to the drill-bit in such a manner as to form a closed water passage that will deflect the water against the cutting faces 6-8 of the drill-bit. The stem 14 is hollow and may be any convenient length and diameter, depending on the total weight of the drill tool desired for the drilling operation. Within the stem 14 is a valve housing 30 which is cylindrical in shape and has the same external diameter as the stem. Immediately above the housing 30 two inlet ports 32 are provided in the stem which open upon a central vertical passage 34 that communicates with the housing. During the downward movement of the drilling apparatus or tools the passage 34 is sealed by a check valve 36. Any suitable form of valve may be used, but in the preferred form of the invention the valve consists of a spherical ball 36 fitting against a shoulder 38 in the passage 34 and held in place by a suitably tensioned spring 40. The spring 40 is secured in place by a cage 42, consisting of a base 44 having four up-

wardly extending arms 48 which serve to hold the spring during compression in axial alignment, and which assure a rapid and accurate seating of the ball valve on its return to the seat after allowing passage of water through the valve port. The usual rope socket 50 is secured to the upper end of the stem by which the tool may be attached to the drilling cable.

The operation of the improved type of drill in the drilling of oil wells is as follows: The cable which is attached to the drill tool is reciprocated in the ordinary manner by a walking beam or spudding arrangement to which it is attached. By the reciprocation of the cable and tool, the cutting edges of the drill come into contact with the material at the bottom of the well and cut away or loosen the material therein. During the drilling operation water is supplied to the well hole in the same manner as in ordinary drilling operations to assist in the cutting and in the removal of loosened material. The same hydrostatic conditions are maintained in the operation with this form of drill as are attained in the ordinary drilling operations, but it is essential with this form of drill that the water level in the well be maintained at a depth above the level of the horizontal passageways 32 when the drill is in its uppermost position. On the upward motion of the drill 10 the liquid contained in the passage is, by reason of its inertia, caused to flow downwardly through the outlet ports 22, 24, and along the flutes 18, 20 to the space which is occupied by the bit when in its lowermost position. At the same time the resulting partial vacuum in the upper part of the chamber below the check valve added to the pressure of liquid above the inlet passage 34 causes the deflection of the ball check valve 36 and causes liquid to flow into the chamber and down through the passage 16. The liquid flowing over the cutting faces of the bit removes adhering mud, sand, etc., and prevents the formation of mud pads. On the downward movement of the tools the liquid occupying the bottom of the hole is forced upwardly between the tools and the walls of the well carrying with it the drill cuttings. During this downward movement the liquid contained in the passage 16 cannot escape upwardly through the tools because of the check valve in the housing 32, and is therefore carried downward with the tools. At the end of the downward stroke the inertia of the liquid in the water passages causes it to continue its downward movement with essentially the same velocity as that of the tools during the downward stroke, and through its inertia promotes the desired circulation through the central passageway of the tool, and out at the end of the drill-bit into contact with

the cutting edges, upwardly between the tools and the well wall, and from thence through the openings 34 back into the central passage of the tool. The level of the water in the hole is maintained above the opening 34 in order to attain the desired circulation, but it is desirable not to have too great a depth of liquid in order to prevent excessive frictional resistance. It has been found in the operation of this apparatus that sand and heavier drill cuttings may be suspended in water containing clay, and held in suspension for a considerable period of time, whereas water which does not contain clay is unable to hold sand and drill cuttings in suspension for any perceptible period. Through the circulation of sludge more and more clay is suspended during the course of the circulation and the sludge is better able therefore to hold sand and heavier materials in suspension. The drilling operation may thus be continued for a much longer period than with the ordinary form of drill, on account of the manner of circulation to prevent the clogging of the drill-bit and to attain the suspension of drill cuttings. This form of apparatus is therefore admirably adapted for drilling deep wells where it is desired to drill for as long a time as possible without the necessity of cleaning the tools and bailing the drill hole.

The exterior form or contour of the drill-bit is substantially the same as that of the standard drill-bit so as to retain all of the advantageous features of the standard bit. The customary water channels 52 at opposite sides of the bit are retained, thereby providing ample room at the center of the cutting edge for the water to pass up between the bit and the well wall, and thus also causing a circulation in the direction from the outer corners of the cutting edge of the bit toward its center and effectively washing the mud away from the cutting edge along its entire length. The cover plates 26 and 28 over the flutes 18 and 20 maintain substantially the same shape on the bit edge as the edges of the standard drill-bit. The shape and position of the cover plates 26 and 28 are important in directing the bit cleaning water on the cutting faces and edges of the drill-bit to maintain an efficient drilling action.

Various changes and modifications of the apparatus may be made without departing from the spirit or scope of the invention.

Having thus described the preferred form of the invention, what I claim as new is:

1. A drilling apparatus comprising a bit having a cutting edge extending substan-

tially transverse to the axis of the bit, said bit having longitudinal channels in the plane at right angles to the longitudinal plane including the cutting edge of said bit, and means for providing a downward draft of water at the corners of said cutting edge. 65

2. A drilling apparatus comprising a bit having a cutting edge extending substantially transverse to the axis of the bit, said bit having longitudinal channels in the plane at right angles to the longitudinal plane including the cutting edge of said bit, and means for providing a downward draft of water at the corners of said cutting edge on the upward stroke of the bit only. 75

3. A drilling apparatus comprising an elongated drill bit having a transverse cutting edge, longitudinal water channels in the sides of the bit, longitudinal water passages extending along the edges of the bit in the longitudinal plane of the cutting edge of the bit and arranged to conduct water therethrough and discharge it directly upon the corners of the cutting edge of the bit, an elongated stem to which the bit is connected, a passage-way connecting with the said water channels and extending through said stem, said passage-way having an opening in the stem positioned a substantial distance above the bit, and a valve mounted in the said passageway arranged to permit downward movement only of the liquid through the passageway and channels. 85

4. A drilling apparatus comprising in combination a drill-bit having a cutting edge, longitudinal flutes leading to the cutting edge of the said drill-bit, a hollow shank, passageways connecting the said flutes with the said hollow shank, plate deflectors covering the said flutes, a hollow stem connected to the said hollow shank, a check valve in said stem permitting downward passage of fluid through the said stem, a passageway to the inlet side of the said valve communicating with the exterior of the said stem to permit circulation through the apparatus, and longitudinal channels on the side of the bit separated from said flutes. 100

5. A drilling apparatus comprising an elongated drill bit having a transverse cutting edge, longitudinal water channels in the sides of the bit and longitudinal water passages extending along the edges of the bit in the longitudinal plane of the cutting edge of the bit and arranged to conduct water therethrough and discharge it directly upon the corners of the cutting edge of the bit. 105

In testimony whereof I affix my signature.

JAMES P. FISHER.
